UNITED STATES PATENT OFFICE.

EDWARD MALLINCKRODT, JR., OF ST. LOUIS, AND HENRY V. FARR, OF FERGUSON, MISSOURI, ASSIGNORS TO MALLINCKRODT CHEMICAL WORKS, OF ST. LOUIS, MISSOURI, A CORPORATION OF MISSOURI.

METHOD OF AND APPARATUS FOR PRESERVING ETHER.

Application filed November 17, 1927. Serial No. 233,980.

This invention relates to a method of, and apparatus for preserving ether, and with regard to certain more specific features, to a new and improved package for ethyl ether.

5 Among the several objects of the invention may be noted the provision of means for protecting packaged ether from certain deteriorating influences exerted by the material comprising the original inner surface of the enclosing package and the provision of means 10 of the class described which are economical in application. Other objects will be in part obvious and in part pointed out hereinafter.

The invention accordingly comprises the 15 elements and combinations of elements, features of construction, arrangements of parts, materials and the combinations of materials and the steps and sequence of steps, which will be exemplified in the following description and the application of which will be indicated in the annexed claims.

In the accompanying drawing, the figure 20 illustrates a cross section of a package for ether to which the present invention has been applied.

Similar reference characters indicate corresponding parts throughout the specification and drawing.

Heretofore the conventional package for 25 ether has comprised a metal can having the general shape of the package shown in the drawing. However, the shape of the can or package is of substantially no consequence in this invention. This previously used can was 30 composed of conventional tin plate formed by the conventional process. During this process but after the tinning operation thereof, the plate passes through a bath of hot zinc chloride which removes dross and oxides 35 from the tin surface. Thereafter the sheet is flushed with hot palm oil, whereby most of the zinc chloride is removed and the formation of an oxide film on the tin surface is substantially prevented.

40 We have found that a clean tin surface, prepared for example by the above process and whether or not in the presence of iron, exerts what is thought to be a catalytic or accelerating effect upon the reaction between ethyl ether and air, whereby ethyl peroxide and/or acetaldehyde is produced.

The tin cans (of which those made by the above process are merely representative) when filled with ethyl ether, have been found

55 to exert the above effect upon the formation of ethyl peroxide and/or acetaldehyde in the ether. The ether, filled in contact with air, carries with it sufficient oxygen for the formation of these impurities, if thus catalyzed. It is conceivable that the effect may be other 60 than catalytic, but in any case the invention described herein is effective independently of the theory of chemical action exerted by the inner tin or similar surface of the can.

The presence of ethyl peroxide and/or 65 acetaldehyde is undesirable both in anaesthetic ether and certain grades of commercial ether.

70 It has been found that the rate of spoilage depends upon the character and extent of the tin or other surface exposed to the ether, the rate of decomposition being a function of the area of active tin. Hence, by cleaning the tin before the cans are used, the active catalytic surface is exposed, to the detriment of the 75 subsequently packaged ether. Even though the palm oil were not undesirable per se, and were left on the tin, the ether cuts through it and thereby permits the detrimental catalytic action of the tin to proceed.

80 It is to be understood that the above remarks, as well as those following, apply to cans made by the above process, or pure-tin cans or others having inner surfaces which are detrimental to the ether.

85 It has been proposed to overcome the detrimental catalytic action of the inner can surfaces by merely introducing into the container an alleged catalyst poison or anti-catalyst.

90 On the other hand, the present invention comprises treating tin containers or similar packages so that a non-catalytic (that is, passive) surface is produced on the inner face of the metal composing the can, said 95 surface thus being devoid of objectionable influence on the ether, whether the ether be in the presence or out of the presence of air. By the term non-catalytic we intend to include such materials as (1) a film of oxide of tin, (2) those varnishes which are insoluble in ether, and (3) lead.

95 Referring to the drawing, numeral 1 refers to the sheet iron which is surfaced on both sides with a coat of tin 3 and formed as 100 a can or package 5.

Numeral 9 indicates the harmless inner passive surface. For the production of this

surface several different methods of treatment have been found to be effective.

(1) The inner surface of the package, or the surface of the sheet material which is to become the inner surface, is treated by washing, dipping or otherwise applying a solution of one of the oxidizing substances, such as potassium permanganate, which has the effect of producing a passive surface on the tin. The result is that the possibility of catalytic or other detrimental action of the tin surface is eliminated. It is preferable to have the entire inner surface of the package treated.

(2) The formation of a harmless surface may also be accomplished by oxidizing the surface in question by exposure to air or oxygen, preferably after having moistened the surface.

(3) Oxidizing may also be accomplished by electrolysis.

(4) Oxidation may be accomplished by heating the metal to an oxidizing temperature.

(5) The treatment may also be effected otherwise than by oxidation; for example, by applying varnishes (such as bakelite) which are insoluble in ether. Solutions of pyroxylin, cellulose acetate, and/or gelatin are also varnishes which on drying form a film insoluble in ether; as indicated in "Pyroxylin Enamels and Lacquers" by S. P. Wilson, (1927, page 29), "The Technology of Cellulose Esters" by E. C. Worden, (1916, Vol. VIII, page 2670), and "The Chemistry and Technology of Gelatine and Glue" by R. H. Bogue, (1922, page 55), respectively.

(6) Surfaces of harmless metals such as lead may also be applied by coating on the iron or tinned iron surface of the sheet material.

(7) Coatings of harmless metals may also be applied by electrolysis.

It will be seen from the above that one of the objects of the invention is to treat the inner surface of the can, so that there is substantially no catalytic or other action between the inner surface and the ether and/or air within can, thus obviating the necessity for using preservatives or other foreign substances.

Furthermore, the invention eliminates the expense of a can composed completely of the non-detrimental substance and, at slight expense, makes the ordinary economical tin can available for packaging ether.

It is to be understood that the tin or other plate may be treated in the manner described before or after the can is formed.

It is also to be understood that the inner surface of the cap 7 may be treated as above described if it is desired to manufacture the cap from material similar to the material composing the can.

By entirely or completely surfacing of the

inside of the can is meant herein, at least the surfacing of the container portion or portions without the cap, since the cap may be composed of non-detrimental material or its area may be so small that its detrimental effect is negligible.

In view of the above, it will be seen that the several objects of the invention are achieved and other advantageous results attained.

As many changes could be made in carrying out the above, without departing from the scope of the invention, it is intended that all matter contained in the above description or shown in the accompanying drawings shall be interpreted as illustrative and not in a limiting sense.

We claim:

1. The ether package comprising a metallic can having a tin oxide coating therein, said can containing ether.

2. A package of ether comprising a tin can, a complete inner surface for said can which is non-catalytic to ether and air placed in said can and a non-catalytic cap therefor, said can containing ether.

3. A package of ether comprising a tin can, a non-metallic inner surface for said can which is non-catalytic to ether and air placed in said can and a non-detrimental cap therefor, said can containing ether.

4. A package of ether comprising a tin can and a complete inner surface for said can which is non-catalytic to ether, said can containing ether.

5. A package of ether comprising a tin can and a complete inner surface for said can which is non-catalytic to ether and which is adapted to completely separate the tin of the can from contact with the contents thereof, said can containing ether.

6. A package of ether comprising a tin can and a complete inner surface for said can which is non-catalytic to ether and which is adapted to separate completely the tin of the can from contact with the contents thereof, said can containing ether.

7. The method of packaging ether, which comprises treating metal for ether containers to form a surface thereon which is non-catalytic with respect to ether, forming the container of said metal, and introducing ether therein.

8. The method of packaging ether, which comprises treating metal for ether containers to form a surface thereon which is non-catalytic with respect to ether in the presence of air, forming the container of said metal, and introducing ether therein.

9. The method of packaging ether, which comprises oxidizing the entire tinned interior surfaces of the package, and introducing ether therein.

10. The method of packaging ether, which comprises oxidizing the tinned interior sur-

- faces of the package over such substantial areas as to prevent substantial deteriorating action by said surfaces on the ether, and introducing ether therein.
- 5 11. The method of packaging ether, which comprises oxidizing the tinned interior surfaces of the package by means of the application thereto of potassium permanganate, and introducing ether therein.
- 10 12. The method of packaging ether, which comprises oxidizing the tinned interior surfaces of the package by means of the application thereto of an oxidizing salt, and introducing ether therein.
- 15 13. The method of packaging ether, which comprises treating tin plate for contact with the ether by producing on the tin surface of the plate a film which is non-catalytic to peroxide formation in the ether, and introducing ether into a package made of said plate.
- 20 14. The method of packaging ether, which comprises treating tin plate for contact with the ether by producing on the tin surface of the plate a film which is non-catalytic to peroxide formation in the ether, said film having an extent which is substantially equal to the normal extent of contact of the ether with the package, and introducing ether into a package made of said plate. 25
15. The method of packaging ether, which comprises oxidizing the entire tinned interior surfaces of the package by contacting said surfaces with an oxidizing material, drying the package, and introducing ether 30 into the package. 35

In testimony whereof, we have signed our names to this specification this 12th day of November, 1927.

EDWARD MALLINCKRODT, JR.
HENRY V. FARR.
